UNITED STATES PATENT OFFICE

CHARLES H. NORTON, OF PLAINVILLE, CONNECTICUT, ASSIGNOR TO NORTON COMPANY,
OF WORCESTER, MASSACHUSETTS, A CORPORATION OF MASSACHUSETTS

AUTOMATIC GRINDING MACHINE

Original application filed September 28, 1925, Serial No. 59,158, and in Great Britain September 6, 1926.
Divided and this application filed June 26, 1928. Serial No. 288,365.

My invention relates to a grinding machine and more particularly to an automatic machine for grinding cylindrical objects. This application is a division of my copending application Serial No. 59,158 filed September 28, 1925, relating to automatic cylindrical grinding machines.

The ordinary plain cylindrical grinding machine is too slow for rapid production of small cylindrical objects, since a large number of operations are required of the operator while the machine remains idle. In using such a machine, when a piece of work has been ground to size, it is necessary for the operator to stop the motion of the machine, turn the feed mechanism to remove the grinding wheel from the work, move the footstock center, and manually remove the piece of work from the centers. He then takes the next rough piece of work to be ground, which has previously been dogged, and inserts it in axial alignment between the centers. This being done, he brings the footstock center into position to support the work and starts the machine in motion, after which he must feed the wheel into the work and occasionally stop to caliper the work and make sure of getting it to size. It will be readily seen that considerable time is lost, by having to perform all these operations, and it is seldom that work is of such a size and character that an operator can run more than one of these machines at a time.

It is an object of my invention to overcome such difficulties and to increase production when a large number of duplicate pieces are to be ground by providing a machine which may be fully or partially automatic in operation and thereby require but little attention on the part of the operator.

A desirable type of automatic grinding machine is one which is so arranged that the work may be placed in a hopper by the operator and from there fed into axial alignment with automatically operated gripping members which support and rotate the work during the grinding operation. The pieces of work should be ground successively by feeding the grinding wheel with extreme precision through a predetermined distance and

then withdrawing it for removal of the finished work and replacement by a fresh piece. To feed the wheel into the work requires a mechanism which goes through a cycle of operations and which is capable of fine adjustments and will produce uniform and duplicate results repeatedly. The operator should be required merely to fill the magazine with rough pieces of work to be sized, and from time to time make slight adjustments to take care of any wear of the grinding wheel.

The automatic grinding machines heretofore proposed have not been wholly satisfactory for various reasons. They have either depended on the action of a chuck to hold and drive the work from one end and a footstock center to support the work on the other end, or they have otherwise required a complicated mechanism to insert new pieces of work into the machine, hold the same during grinding, and thereafter discharge it.

It is accordingly another object of my invention to utilize a work supporting and rotating mechanism in which the work is gripped between two positively rotated spindles and supported by pressure against the ends of the piece so as to give a frictional driving contact between the spindles and the work, and thereby to provide a simple work supporting device which permits quick replacement of the work and efficient operation of the machine without the necessity of chucking or centering the work.

It is a further object to provide an automatic mechanism capable of feeding pieces of work successively to the work supporting and rotating members and which is operated in timed relation with the movement of the cooperating work support and wheel feed mechanism so as to insure efficient and rapid operation of the machine.

It is a further object to provide a work supporting mechanism which will automatically grip successive pieces of work of different sizes in a yielding and cushioned manner, and particularly to so arrange this mechanism that the work supporting members may be brought into contact with the work by an adjustable pressure device but positively

withdrawn by a power operated mechanism, and thereby insure safety in the operation of the machine.

A further object is to provide a fully automatic grinding machine in which the work pieces are successively gripped by and released from work supporting members, and to provide mechanism co-ordinating such an operation with the wheel feeding movement, so that they will be carried on in a proper timed relation.

With these and other objects in view as will be apparent to one skilled in the art, my invention resides in the combination of parts set forth in the accompanying description and covered by the claims appended hereto.

I have illustrated in the drawings a machine including all of the various features of my invention so arranged as to operate automatically, but certain of these features may be incorporated, as desired, in a semi-automatic machine intended to be manually controlled for grinding a single piece of work at a time, and it is to be understood that such subcombinations fall within the scope of my invention.

Referring to the drawings in which like reference numerals indicate like parts:

Figure 1 is a front elevation of my automatic grinding machine having portions broken away to more clearly show the inside mechanism;

Fig. 2 is an end elevation of my machine, with portions of the base similarly broken away;

Fig. 17 is a fragmentary end elevation partly broken away showing a modified form of work presenting mechanism; and

Fig. 18 is a fragmentary rear elevation of the mechanism shown in Fig. 17.

In my preferred construction, I have illustrated an automatic grinding machine in which the work is placed in a hopper and is then fed automatically into axial alignment with a pair of rotatable work supporting spindles, which are arranged to move toward the ends of the work to grip it adjacent its periphery for rotating it by frictional contact. In order to feed the grinding wheel and the work relatively towards each other,

one of these, and preferably the wheel, is mounted on a slide, and this slide is moved precisely by means of a cross feed screw mechanism. This is operated by a power

drive which is preferably controlled by a cam so as to move in timed relation with the work supporting spindle mechanism. I prefer to feed the slide forward by an adjustable weight and to move it back positively by the cam mechanism, and I so arrange the

parts that the grinding wheel is fed rapidly at the start and then with a slow and uniform feeding motion until the work has been reduced to its approximate size, at which point the feed mechanism engages a stop which

prevents further feeding movement of the grinding wheel and permits the wheel to grind out or finish grind the work. The cam is preferably so shaped that when the work

has been finished, it moves the slide rapidly in the opposite direction to remove the grinding wheel from the work. Likewise, the work gripping mechanism is preferably operated in one direction to grip the work by

an adjustable weight and in the opposite direction by a power driven cam.

The work may be fed to the work supports by hand or automatically, as by means of a turret wheel which is moved in timed relation with the spindles to present the work thereto and then remain stationary during the grinding operation. The turret may be moved positively by a power drive or the weight of the work may be utilized to rotate it, and a cam operated control device insures that the wheel remain immovable except

when release of the finished work and feeding of a new piece is required. I also provide a wheel spindle reciprocating mechanism to oscillate or reciprocate the grinding

70

wheel spindle axially through a short distance so that the wheel will wear evenly and prevent the formation of grain markings on the work being ground.

Referring to the drawings, I have there shown the machine base 10 as made in two parts, one the front base 11 and the other the rear base 12 (Figs. 1 and 2). The rear base 12 carries the usual grinding wheel slide 13 which is adapted to slide transversely on the usual V-way 14 and flat way 15 mating with corresponding ways on the base. The grinding wheel slide carries a grinding wheel spindle which is mounted in suitable bearings in the wheel slide and carries on one end a grinding wheel 19, as clearly illustrated and described in my prior Patent No. 1,443,924.

A pair of rotatable axially slidable work supporting spindles 20 and 21 (Figs. 1 and 20) are journaled in the front base of the machine in two pairs of bearings 22 and 23 respectively, which may be of suitable construction. These spindles are preferably so arranged that they may be driven in synchronism with each other so as to produce a proper rotation of the work.

Power driving mechanism

As shown in Fig. 2, the rear base is provided with a main drive shaft 30, driven by any suitable source of power, which carries a pulley 32 to transmit power to the wheel spindle 18 by means of a belt 33 passing over a pulley 34 on the wheel spindle 18 and an idler belt tensioning pulley 35. Power may be transmitted to the front base of the machine from the main drive shaft 30 by a sprocket 40 thereon and a link drive chain 41 to the sprocket 42 on the shaft 43. The sprocket 42 is rotatably mounted on the shaft 43 and is so constructed that it may be connected or disconnected from the shaft by means of a suitably constructed clutch 44 which is operated by the usual yoked member 45 pivoted to the base at 46 and the manually operable lever 47. The shaft 43 is connected by a coupling 49 to the shaft 50 which carries a spur gear 51 meshing with a spur gear 52 on the short shaft 53. The shaft 53 carries on its other end a spur gear 54 meshing with a spur gear 55 on the cross shaft 56 which extends the length of the machine. This shaft 56 carries the sprockets 60 and 61 respectively which drive the link chains 64 and 65. These in turn drive the sprockets 66 and 67 on the work supporting spindles 20 and 21 respectively. The chains 64 and 65 are of sufficient length and have enough flexibility so that the sprockets 66 and 67 may be fixed to the axially slidable work spindles 20 and 21.

The gears 54 and 55 are preferably change gears and are so constructed that they may be readily removed and replaced by other

combinations to vary the work rotating speed. These gears 54 and 55, as illustrated, are arranged to give a slow speed rotation of the work support spindles. By removing them and placing the larger gear 55 on the shaft 53 and the smaller gear 54 on the shaft 56 the speed of rotation of the work supporting spindles may be increased.

To permit tensioning the link drive chains 64 and 65, I preferably mount the shaft 56 in the two swinging brackets 70 and 71 (Fig. 13) which are arranged to swing about the axis of the shaft 53 as a pivot, so that for any position of the shaft 56, the gears 54 and 55 are always in mesh. The brackets 70 and 71 are each provided with an elongated slot 73 and a set screw 74 which passes through the elongated slot and is screw threaded into a portion of the base of the machine. It will thus be readily seen that the brackets 70 and 71 may be separately adjustable and locked in a desired position, so that either of the chains 64 and 65 may be tensioned without disturbing the driving tension of the other.

Cross feed mechanism.

One of the main features of my invention has to do with obtaining a precise and duplicatable feeding movement of the wheel into the work. To this end, I mount one of these, and preferably the grinding wheel, on a cross slide and connect a feed screw thereto. This feed screw is rotated automatically by a power mechanism, and the rate of rotation and direction of movement is accurately controlled by a further automatic device, which is preferably a cam, so that the wheel is fed forward a predetermined amount and then withdrawn. Successive pieces of work may be brought to the same exact size by utilizing an adjustable stop so arranged that the feed screw may not be turned beyond a certain point, irrespective of the operation of the cam and power drive therefor. The power is best applied by means of an adjustable weight arranged to feed the wheel into the work as permitted by the cam, and the latter serves to withdraw the wheel and lift the weight for the next infeed operation.

A further important feature lies in a construction which permits one to vary the length of the feeding stroke without changing the cam. This is simply accomplished by connecting the cam with the screw by means of a chain passing over a sprocket on the screw shaft and adjustably connected to an involute shaped lever which is oscillated by the cam. The point of connection of the chain with the lever may be adjusted to change the effective length of the lever arm, and this serves merely to wrap the chain about the sprocket without turning the screw.

While the slide may be moved by various types of cross mechanism, I prefer to em-

ploy one which is patterned generally after that shown in my prior Patents No. 762,838 and No. 1,443,924. This mechanism comprises a half-nut 80 secured to the under side 5 of the wheel slide 13 which is screw threaded to engage a plurality of corresponding threads on a feed screw 81. The feed screw is journalled in the rear base of the machine and carries on its front end a gear 83 meshing 10 with a pinion 84 on the shaft 85 journalled in the front base of the machine. The shaft 85 carries a gear 86 meshing with a gear 87 on the shaft 88, on which is mounted the gear wheel 89 arranged to turn the feed screw. 15 The hand feed lever 92 is rotatably mounted on a projection of the shaft 88 and carries a micrometer adjusting mechanism 93, such as is clearly described in my prior Patent No. 762,838; and the patent to Wilcox No. 20 1,261,083. This mechanism permits adjusting the feed arm 94 relative to the gear wheel 89, and comprises a pinion 95 meshing with the gear 89 and a crank arm 96 adjustably clamped to the extension 97 of the pinion 25 shaft 95. By pulling the plunger 98 from the opening 99 in the index plate 100, the crank arm 96 may be turned the desired amount to adjust the arm 94 relative to the gear wheel 89. When in adjusted position the plunger 98 30 may be reinserted in the nearest opening 99 in the index plate 100. This makes it possible to position the grinding wheel as desired relative to the work, to adjust for wheel wear, or even to feed the wheel by hand when 35 considered necessary.

Cam controlled power drive for feed screw

The feed screw is rotated by a cam mechanism, including a cam and a follower operatively connected to the feed screw, which is so 40 constructed and arranged that the distance and rate of travel of the wheel into and away from the work are predetermined in accordance with the contour shape of the cam. The 45 embodiment illustrated comprises an adjustable weight connected to the screw by a chain and sprocket, and the movement of the weight is controlled by a power driven cam. To this end, I may mount a cam 110 on the 50 shaft 111 which is journalled in the front base of the machine. To positively rotate the cam 110, a worm 112 is mounted on the shaft 50 (Fig. 1) in mesh with a worm gear 113 mounted on the shaft 114. The other end 55 of the shaft 114 carries a gear 115 (Figs. 2, 3 and 4) which in turn meshes with an intermediate gear 116, arranged to drive a gear 117 on the cam shaft 111 to rotate the cam 110.

To permit varying the speed of rotation of 60 the cam and consequently the speed at which the grinding wheel is fed inwardly, I employ a suitable change gear mechanism. This may be simply accomplished by mounting the gear 116 on a swinging arm 120, which swings 65 about the axis of the cam shaft 111 as a pivot.

The small gear 114 is preferably a change gear which is so constructed that it may readily be slipped into place or taken off and changed for a larger or smaller gear. The 70 arm 120 is preferably a bell crank, having a projecting arm 121 by which the gear 116 may be swung into mesh with the change gear 115. The gear 116 is locked in its adjusted position by a clamping screw 123, which slides within the arcuate slot 124 in the member 125. This member 125 is fixed inside the machine by the threaded studs 126 (Fig. 2). 75

To transmit the motion of the cam 110 so as to control the movement of the feed mechanism, I mount a lever 130 (Figs. 1, 8 and 12) on a pivot 131 on the base of the machine. The short arm 132 of the lever 130 carries a follower roller 133 which is adapted to engage the operative surface of the cam 110. A radially extending arm 135 having a projecting hub 136 is journalled on the shaft 88 and is provided at its outer end with a locking screw 137 adapted to lock the arm 135 to a projection of the arm 94. The member 135 carries a sprocket 138 on its projecting hub 136. To transmit the cam motion from the lever 130 to the feed mechanism, I employ a link chain 140 which passes over the sprocket 138 and has one end adjustably connected to the arm 145 by a slidably clamping member 142. The lower end of the chain 140 is connected to a weight 143 which is slidably mounted in the housing or bracket 144 secured to the base of the machine. The weight 143 is of sufficient size to turn the feed screw to feed the grinding wheel into the work and to keep the cam follower roller 133 always in contact with the surface of the cam 110. 90

The feed cam 110 is preferably of such a 100 shape that it will cause the grinding wheel to be fed rapidly toward the work for a short period of time until it is about to contact with the work, and thereafter be moved at a slow and uniform rate until the work has been reduced to its approximate size. During the final stage of grinding the feed mechanism is held immovable by a stop mechanism for a short period of time to permit the grinding wheel to finish the grinding operation. 110

From this disclosure, it will be readily seen that the weight 143 turns the feed screw as limited by the shape and motion of the cam 110 to produce the feeding action of the grinding wheel toward the work. The return motion of the grinding wheel caused by the abrupt rise on the cam positively turns the feed screw in the opposite direction against the action of the weight 143, and moves the grinding wheel rearwardly to its initial position. 120

Feed stop device

To positively limit the infeed of the grinding wheel at a predetermined point, I pro- 130

vide a stop screw 146 adjustably held in position by a locking nut 147 in a bracket 148 fixed to the front of the machine base (Figs. 1, 9 and 12). The bracket 148 is so shaped and positioned on the base that the screw 146 is in the path of the outer abutment 149 of arm 135. The stop screw 146 is preferably so adjusted that the arm 135 contacts with the screw 146 before the cam follower roller 133 reaches the end of the infeed portion of the cam. With this adjustment, it will be readily seen that the stop screw 146 positively limits the feeding movement of the grinding wheel at a predetermined point, since the cam mechanism acts, not directly upon a massive wheel slide, but upon the feed screw, and it is possible to turn the latter with a fine degree of precision and therefore feed the grinding wheel exactly to a predetermined position and reduce pieces of work to a desired size successively and uniformly. Moreover, when the stop becomes effective, the feed control cam may continue to rotate but the stop holds the cam follower out of contact with the cam until it is time to move the wheel away from the work; hence, the stop acts positively to limit the infeed of the grinding wheel.

Adjustment of feeding stroke

The feeding motion of the cam is limited by the size and shape of the cam. In order that the amount of feeding movement per cycle may be varied, I preferably make the upper arm of lever 130 as an involute shaped arm 145. By shifting the position of the slideable clamping member 142, which is secured to the end of the link chain, along the arm 145, I change the effective length of the lever arm 145 and consequently vary the amount of feeding movement. The nearer the clamping member 142 is to the pivot point 131, the less the feeding movement. The greater the distance away the clamping member 142 is from pivot 131, the greater the distance through which the mechanism will feed the wheel into the work.

By making the lever 145 in the shape of an involute of a circle, the clamp 142 may be adjusted along the lever without changing the relative position of the link chain and therefore without disturbing the position of the feed screw, since the chain merely wraps itself around the sprocket 138 and does not turn the screw when such adjustment is made.

In setting up the feed mechanism for any particular piece of work to be ground, the clutch 44 is thrown out of engagement and the work is mounted on the work supporting spindles. The locking screw 137 is then disconnected from the projection of the feed arm 94 so that the radially extending arm 135 swings downwardly into contact with the stop screw 146. The feed mechanism is

now free so that the grinding wheel may be fed manually into the work.

The feed cam 110 is then rotated by manually turning the shaft 111 by placing a wrench on the projection 134 until the follower roller 133 is a short distance from the abrupt rise in the cam. The feed mechanism is then turned by means of the hand lever 92 until the grinding wheel reaches a position where the work has been reduced to its desired size. By withdrawing the micrometer adjusting plunger and turning the pinion relative to the feed gear, the feed arm 94 swings into substantial alignment with the arm 135 so that the locking screw 137 may be screwed into place and lock the feed mechanism to the arm 135. It may be necessary at this point to adjust the micrometer device slightly to bring the arm 135 into contact with the stop screw 146. It also may be necessary to make a slight adjustment of the stop screw 146 to be sure that the cam follower roller 133 does not touch the operative surface of the cam for a short distance before the abrupt rise is reached. If this adjustment is necessary, the operator will also have to make a further readjustment of the micrometer device to bring the work to the desired size.

In view of the above explanation, it will be understood that the feed screw is rotated through a definite distance and at a predetermined rate controlled by the contour shape and rate of movement of a cam, so that the grinding wheel moves cyclically and repeatedly through the same path of advance and retreat, or what may be termed "an invariable cam cycle". The distance through which the wheel moves is therefore a function of the extent of a single rise and fall of the follower on the cam, and this may be varied by making adjustments of the stop and of the location of member 142 on the arm 145. These adjustments make it possible to regulate the rate of feed, as well as the distance of travel of the wheel, so that the grinding operation may be controlled as desired. It will also be understood that the adjustable stop makes it possible to grind with even greater precision of measurement than can be obtained by the use of the cam alone, since the stop may be set to stop the infeed of the wheel before the cam follower has reached the extent of its throw, i. e. the lowest point on the cam, and thereby prevent further infeed of the wheel and permit the grinding operation to die out gradually and so produce a fine finish on the work.

Work gripping and supporting mechanism

Another important feature of the invention is the provision of a power operated mechanism for gripping and centering the work and thereafter rotating it for the grinding operation. This may be accom-

plished by means of a yielding device which is preferably weight operated to close the gripping members on the work, and a power operated positively acting mechanism to release the work, which parts move in timed relation with the wheel feed mechanism.

I have found that such a work gripping and rotating device, to be effective, must engage the work close to the periphery thereof, so that the torque and the friction of the rotating members may be as high as possible, as compared with the retarding effect of the grinding wheel on the work. If the work is gripped only near its center line, there is a serious possibility of slippage and consequent imperfect grinding. My device is so arranged that it automatically centers the work, and it is not necessary to first provide the work with center punch markings or to make other provisions for this purpose. The particular type of work gripper used depends upon the shape of the work to be ground. In some cases, I employ members which engage only the ends of the work. If the work is hollow, I may utilize spring fingers fitting within the work to assist in supporting it.

In my preferred construction, shown in detail in Figs. 3 and 4, I provide a simple arrangement for moving the work gripping members which is operated by a cam controlled weight and linkage mechanism. As shown, the spindles 20 and 21 are axially movable and carry work gripping members at their inner ends which are forced into contact with the work and are rotated by the spindles. These spindles are moved axially by levers 150 and 151 pivoted to the bases 152 and 153 respectively. The upper ends of these levers are each provided with yoked portions 154 and 155 which are connected to move the spindles, which carry the work gripping members, axially towards and from the ends of the work. The lever 151 is shaped like a bell crank and has a downwardly extending portion 157 connected by the pivot pin 158 to the connecting rod 159. To move the two levers simultaneously in opposite directions, I provide the lower end of the lever 150 with a gear tooth projection 162, meshing with the teeth or projections 163 on the substantially T-shaped lever 164. The lower arm of the T-shaped lever 164 is connected by the pivot pin 165 to the connecting rod 159. The long arm 168 of the T-shaped lever 164 supports through the rod 169 an adjustable weight 170. This mechanism, as clearly shown in Figs. 1, 3 and 4, is such that the weight normally acts to hold the work supporting members towards each other to grip the opposite ends of the work piece with an equalized pressure.

To separate the work supporting spindles 20 and 21 and thereby release the finished work and permit a new piece to be put into position for grinding, I provide an adjust-

able, positively actuated intermittent mechanism operating in timed relation with the wheel feeding mechanism. To this end, I provide a revoluble member arranged to strike the lower end of one of the spindle actuating levers and force it to move the grippers outwardly. As illustrated, I employ a roller 180 carried by the adjustable arm 181 rotatably mounted on the cam shaft 111. A projecting arm 182 is mounted in fixed position on the cam shaft 111 and provided at its outer end with an adjusting screw 183 and lock nut 184. The outer end of the adjusting screw 183 bears against the projection 186 of the lever 181 so that the roller 180 carried by the arm 181 may be adjusted angularly relative to the operative face of the cam 110. This insures operating the work supporting spindles in timed relation with the movement of the grinding wheel slide. Depending from the pivot 158 on the bell crank 157 is an adjustable arm 187 carrying a pin or projection 188 so constructed and positioned that it is in the path of the roller 180. As the cam shaft 111 rotates, the adjusting screw 183 carries the roller arm 181 and the roller 180 about its axis. The roller 180 contacts with the pin or projection 188 and swings the linkage mechanism towards the left, thus moving the arms 150 and 151 outwardly to separate the work gripping members on the supporting spindles. This construction provides means for yieldingly moving the spindles towards each other, so as to make the machine safe in its operation, and insures a positive separation of the spindles when the work has been finished.

Adjustments for work supports

To vary the amount of movement of the work supporting spindles, I preferably mount the arm 187 so that it pivots about the pin 158. A projection 190 on the arm 187 is provided with an elongated slot 191 so arranged that the arm 187 may be locked in adjusted position to the lever 157 by a nut and screw 192 which passes through the slot 191. By swinging the arm 187 towards the right, one reduces the amount of motion transmitted to the work supporting spindles because the roller 180 will strike the pin 188 only at the upper portion of the roller and so contact therewith later and leave it sooner than would be the case if the pin 188 were lowered to be struck by the roller near a horizontal diameter. As shown in the drawings, the arm 187 is adjusted to the extreme left hand position to give a maximum relative movement to the work supporting spindles.

To vary the distance between the work supporting spindles, I provide the spindles 20 and 21 with threaded portions 200 and 201. Surrounding these threaded portions are a pair of double race ball bearings 202 and 203 which engage the yoked portions 154 and

155 of levers 150 and 151 respectively. To adjust the positions of the ball bearings relative to the spindles, I provide a pair of nuts 204 and 205 so arranged that the ball bearings may be moved along the threaded portions 200 and 201 and then locked in position. This adjustment varies the distance between the work engaging members on the spindles to accommodate different lengths of work.

10 As a further means of varying the distance between the work supporting spindles to accommodate various lengths of work, I make the connecting rod or link 159 adjustable in length. This is preferably accomplished by 15 means of a turnbuckle or other suitable arrangement. As shown, I may screw thread each end of the rod 159 and mount the threaded couplings 206 and 207 thereon. Lock nuts 208 and 209 are provided respectively to lock 20 the couplings in adjusted positions. After removing the pivot pin 165 from the pivotally mounted coupling 206 and loosening the lock nut 208, the operator may turn the coupling 206 relative to the rod 159 to shorten or 25 lengthen the distance between pivots 165 and 158 and thus vary the distance between the ends of the work supporting spindles. Likewise the other pivot pin 158 may be removed and the coupling 207 adjusted if a further ad- 30 justment is necessary.

To prevent a rapid dropping of the weight 170 and consequently a too sudden motion of the spindles 20 and 21 in gripping a new piece of work, I preferably mount the weight 170 so that its lower portion acts as a dash-pot piston (see Fig. 3). The piston or weight 170 is surrounded by a dash-pot cylinder 210 which is provided with an opening to the atmosphere controlled by an adjustable air 35 valve 211 so arranged that the leakage of air may be regulated to cushion the motion of the weight. By varying the weight 170 and the adjustment air valve 211, the spindles may be moved slowly or rapidly towards each 40 other and held in frictional contact with the ends of the work to be ground with sufficient pressure to support and rotate the work during the grinding operation.

The bottom of the dash-pot cylinder 210 is provided with a series of openings or holes 212 to allow air to leak rapidly into the cylinder on the up stroke of the piston or weight 170 and prevent retarding the releasing movement of the work supporting spindles. To 45 prevent air escaping from the cylinder through the holes 212 during the downward motion of the piston, I place a soft, flexible disk 213 of leather, rubber or the like in the bottom portion of the cylinder. The disk 213 acts as a valve and prevents the escape of air on the downward movement of the piston, but permits air to readily raise the disk and enter the cylinder on the upward movement 50 of the piston.

Work feeding mechanism

To make the grinding machine fully automatic I provide means for feeding the work automatically into grinding position on the machine. As illustrated in Figs. 5, 6 and 7, 70 my preferred form of magazine feeding device comprises a turret wheel 230 having openings in its periphery to receive the pieces of work from the hopper 231. The operator places the new pieces of work in the hopper 231 and they roll down the surface 232 and into pockets 233 formed in the two disks 234 which make up the turret wheel 230. This wheel is suitably mounted to rotate about an axle 235 carried on uprights 236 supported on the machine base. A projecting lug 237 is mounted on the inside surfaces of each upright 236 to prevent the new piece of work 238 dropping into pocket 233 in the turret 80 while grinding is going on, and at the same time keeping two pieces from getting into the pocket at once. When the turret wheel rotates, the piece supported on the shelf formed by lugs 237 is forced into the adjacent pocket, and another piece of work rolls onto the shelf in the next pocket as it comes into position.

The turret wheel 230 may be rotated to present new pieces of work to the work supporting spindles by any desired means, but in my preferred construction, I utilize the influence of gravity to turn it and employ a cam operated mechanism to release the turret when the spindle gripping members have dropped the finished piece of work, and permit it to turn just enough to present the next piece to the work supports. To this end, I provide the side of the turret 230 with a ratchet wheel 240. A ratchet pawl 241 is 95 slidably mounted in the boss 243 which is fixed to the upright 236. The ratchet pawl is held by spring pressure in engagement with the teeth of the ratchet wheel 240 to prevent rotation of the turret wheel in a direction 100 to feed the work. To release the pawl 241 from the ratchet wheel 240 and permit the influence of gravity to act on the new pieces of work to turn the turret wheel, I preferably 105 connect the ratchet pawl to the connecting rod 244 (Fig. 8), the other end of which is adjustably connected to the lever 245 pivotally mounted on the side of the base. The lower end of the lever 245 is provided with a cam face 246 adapted to be engaged by a second lever 247 pivoted to the base by a cap screw 248. The lever 247 is connected by means of a connecting link 249 to a projecting portion of the follower lever 132 so that motion of the cam follower 133 due to 110 the abrupt rise portion of the cam is transmitted to raise the lever 247 and cause it to swing and contact with the cam portion 246 and thereby move the lever 245 to withdraw the pawl 241 from engagement with the 115 120 125 130

ratchet wheel 240. This permits the force of gravity acting upon the new pieces of work in the turret wheel 230 to turn the wheel rapidly to bring the next piece of work into axial alignment with the work supporting spindle.

To keep the turret wheel 230 from rotating too far and permit it to rotate just sufficiently to bring the next piece of work into axial alignment with the work supporting spindles, I provide the ratchet wheel 240 with the same number of ratchet teeth as there are work openings in the turret wheel 230. A reduced portion of the ratchet pawl 241 within the projection 243 is surrounded by the spring 242 which exerts a sufficient pressure to hold the pawl in position in contact with the ratchet wheel. The cam face 246 of the lever 245 is so shaped that the ratchet pawl may return rapidly into contact with the next ratchet tooth under the influence of the spring 242 as soon as the lever 247 passes over the cam face 246. This movement is sufficiently rapid so that the pawl catches in the notch next to the one from which it has just been released, and so stops the wheel when the next work piece is opposite the spindles.

In order that the lever 247 may ride downwardly over the cam face 246 without removing the pawl from the ratchet wheel, I preferably make the lever 247 (see Figs. 8, 10 and 11) in two parts. As shown in Fig. 11, the outer swinging portion 251 is pivotally mounted to the lever 247 and is so shaped that on the upward movement, the lever 247 and portion 251 act as a single lever. On the downward movement, however, the portion 251 contacts with cam face 246 and swings upwardly so that it may pass by the cam face 246 without moving the ratchet pawl. When released from the supporting spindles, the piece of work that has been ground falls slightly into contact with its pocket and remains there to aid in turning the wheel to bring the successive pieces of work into their proper grinding positions. As shown in Fig. 5, the piece of work remains in the wheel until it is free to roll downwardly into a container 250 on the front base of the machine.

To position the pieces of work axially, I provide one of the uprights 236 with a spring 252 which projects so as to press against one end of the piece of work and force it to the right, as shown in Fig. 6, against the opposite upright or support 236 of the wheel 230 so that each piece of work is presented to the spindle in the same relative position. This spring 252 is preferably provided with an adjusting screw 254 threaded into the support 236 so that the tension of the spring may be adjusted.

Work supporting devices

Of the various forms of work gripping and supporting devices which I may employ, I

have illustrated two types (see Figs. 3 and 14) which are adapted for holding solid and hollow pieces respectively. In the form shown in Fig. 3, I utilize the cup centers 255 and 256 which are so shaped that they contact with the ends of the work 257 only adjacent the periphery of the work to center and drive the same. The weight 170 and linkage mechanism which are connected to move the work gripping members 255 and 256 axially are so adjusted that the weight holds these members against the work with sufficient pressure to rotate and center the work during the grinding operation.

The device shown in Fig. 14 is particularly useful where it is desired to grind the outer cylindrical surface of a work piece concentric with an internal cylindrical surface. In this case, the spindles 20 and 21 are each provided with tapered apertures 260 and 261 respectively to receive the correspondingly tapered members 263 and 264. The outer ends of the members 263 and 264 are provided with the reduced portions 265 and 266 respectively which are adapted to center the work by its central opening. The portions 265 and 266 are preferably constructed with spring fingers formed by cutting radially extending slots 268 and 269 in the reduced end portions, these serving to center the work even though there are slight variations in the diameter of the holes or openings 270 in the work. The work is gripped between two collars 272 and 273 which are slidably mounted on the spring finger ends 265 and 266. The outward movement of these collars is limited by the shoulders 274 and 275 on the tapered spindle members 263 and 264. The inner ends of the collars are adapted to frictionally engage the ends of the work with sufficient pressure to rotate the work during the grinding operation.

To permit the spindles to withdraw from the finished work, I employ shedder members 276 and 277 mounted on the work supporting spindle housings on the front base of the machine. These shedder members extend downwardly and serve as yoke arms which engage the annular grooves 278 and 279 in the slidable members 272 and 273. When the spindles 20 and 21 are withdrawn to release a finished piece of work, the slidable members 272 and 273 are held against axial movement by the yoke members 276 and 277. This permits the portions 265 and 266 to slide within the members 272 and 273 and withdraw from their supporting position in the opening 270. As the spindles 20 and 21 withdraw, the shedder members hold the slidable members 272 and 273 against endwise movement so that the work supporting spindles 20 and 21 may withdraw from their gripping positions against the ends of the work. This permits the turret wheel to be rotated to

bring the new piece of work into axial alignment with the work supporting spindles.

Power driven turret wheel

5 It may be desirable in grinding some kinds of work to provide a turret wheel which is positively rotated to bring the new pieces of work successively into axial alignment with the work supporting spindles. To accomplish this, I may provide a mechanism which 10 will operate intermittently to positively rotate the turret wheel to bring the work into grinding position. As shown in the drawings, such a construction comprises a turret 15 wheel composed of the disks 234^a having pockets 233^a to receive the pieces of work as they roll down the surfaces 232^a of a hopper. The turret wheel is mounted for rotation on a shaft or stud 284 supported in the 20 uprights 285 and 286 mounted on the machine base. A sprocket 287 is fixed on the wheel hub in the space between the disks 234^a. A supporting bracket 288 is mounted on the machine base and has a shaft 289 journalled therein which carries a sprocket 290 25 on its outer end connected by a link chain 291 with the sprocket 287 to rotate the turret wheel.

To cause the shaft 289 to turn the turret wheel at a proper time, I may connect this 30 shaft with the wheel feed mechanism so that the work will be fed in timed relation with the movement of the grinding wheel. To accomplish this, I mount a ratchet wheel 293 on the other end of the shaft 289 and provide a ratchet pawl 294 on the bracket 295 which swings about the axis of the shaft 289 to pick up the successive teeth of the ratchet wheel 293. To actuate the pawl, I provide 35 a connecting rod 299 which is connected to the lever 130 so that as the feed cam 110 turns the lever 130 is moved to revolve the turret wheel and bring successive pieces of work into grinding position. To prevent excessive rotation of the turret wheel which would 40 carry the new piece of work past the grinding position, I may employ a friction device, which, as illustrated, comprises a friction collar or washer 296 held in frictional contact with the projection 297 of the turret 45 wheel to retard the rotation thereof. I provide adjusting screws 298 which are screw threaded into the upright 286 and bear against the outer face of the collar 296 to 50 vary the frictional contact between the washer 296 and the projection 297. By tightening or loosening the screws 298 the friction between the collar and the turret wheel may be varied as desired.

55 A further modification of a turret wheel is shown in Figs. 17 and 18, in accordance with which I utilize the weight and force of the water stream, which is used to cool the work during the grinding operation, in order to aid 60 in turning the wheel. The wheel is essen-

tially the same as that shown in Figs. 5 and 6 and is operated by means of the cam controlled mechanism shown particularly in Fig. 8; but it is provided with pockets, and shaped somewhat like a water wheel, so that water 70 may enter the pockets on the descending side nearest the grinding wheel and escape only when the pockets successively reach the bottom of their circular path of revolution. As illustrated, the work pieces 300 are supported 75 on the sides 234^b of the wheel, recesses 303 being cut therein to form projecting lugs 304 which curve in such a manner as to hold the work in place. The peripheral portion 305 of the wheel which connects the sides is cut 80 away to form spaced openings 306 and a set of curved walls 307 are formed, as shown in Fig. 17, in such a manner as to provide deep pockets to hold liquid. The sides 234^b form 85 the ends of the pockets and prevent the escape of liquid therefrom until the work has passed below the grinding wheel 19 and is to be discharged. The ratchet 240^b corresponds with the ratchet 240 shown in Figs. 5 and 8, and it is by means of this ratchet control mechanism 90 that the rotative movement of the wheel is regulated. The stream of water, diagrammatically illustrated as issuing from the pipe 310 which is normally used in a machine of 95 this type, strikes against the adjacent openings of the pockets to the wheel, and fills the pockets, and the weight of the water, in addition to the weight of the work, serves to give the wheel a quick rotary movement when the ratchet is released.

100 The operation of the various mechanisms of the machine is apparent from the above description. In this machine, which is fully automatic in operation, the work is placed in the hopper 231 from which it rolls into successive pockets in the turret wheel 230. This wheel is rotated in timed relation with the other machine parts to carry the piece of work into substantial alignment with the work supporting members 255 and 256. At this point, the spindles 20 and 21 carrying the work supporting members are moved axially toward each other to grip the work and raise it slightly from the turret to support and rotate the work during the grinding operation. This is 105 accomplished by means of the weight 170 which moves at a rate determined by the valve adjustment of the dash-pot 210. The motion of the weight is transmitted simultaneously 110 to the two spindles by the linkage mechanism 115 shown in Fig. 3.

120 The cam controlling mechanism shown in Figs. 1, 2, 8 and 12 is constantly rotating, so that when the cam roller 133 has passed over the sharp rise in the cam 110, the cross feed screw 81 will then be rotated by the weight 143 in such a direction as to feed the grinding wheel into the work. This goes on until the arm 135 which rotates with the feed screw 125 strikes the adjustable stop screw 146. For a 130

short time thereafter, the roller 133 is held out of contact with the cam while the grinding wheel finish grinds the work. During this interval the cross feed mechanism is stationary.

Then the cam roller 133 starts up the steep rise of the cam 110 and moves the grinding wheel back rapidly against the pull of the weight 143. When the wheel is out of contact with the work, the roller 180 which is revolved by the cam shaft 111 then strikes the projecting member 188 on the spindle operating mechanism and thereby forces the spindles to separate and withdraw the work supporting members from engagement with the ends of the work. The work then drops into its former position on the turret wheel, and a ratchet mechanism (see Fig. 8) operating in timed relation with the wheel cross feed mechanism is moved to release the turret wheel and permit it to revolve under the influence of gravity and bring the next piece of work into substantial alignment with the work supporting members, and the cycle of operations is then repeated.

Having thus described my invention, what I claim as new and useful and desire to secure by Letters Patent is:

1. A grinding machine comprising a base, a grinding wheel rotatably mounted thereon, a pair of aligned, rotatable, axially movable, work supporting spindles arranged to grip and rotate a work piece during grinding, means to move the wheel towards and from the work, and a single operating device to move both of said spindles simultaneously through the same distance to grip the work, which acts in timed relation with the wheel movement.
2. A grinding machine comprising a base, a grinding wheel rotatably mounted thereon, a pair of aligned rotatable work supporting spindles, each of which is movable axially toward and from the other to grip and rotate a work piece in operative engagement with the grinding wheel, and means to vary the pressure with which the work spindles grip the work during grinding to equalize the pressure thereof on the work.
3. A grinding machine comprising a base, a grinding wheel rotatably mounted thereon, aligned rotatable axially movable work supporting spindles to support and rotate a work piece, means including a cam mechanism to feed the grinding wheel toward and from the work through an invariable cam cycle to grind the work, means operating in timed relation with said cam mechanism to grip and release a work piece before and after grinding it and means to adjust the time at which the work piece is gripped and released.
4. A grinding machine comprising a base, a grinding wheel rotatably mounted thereon, rotatable axially movable work supporting spindles to support and rotate a work piece,

means including a cam mechanism to feed the grinding wheel toward and from the work through an invariable cam cycle to grind the work, means operating in timed relation with said cam mechanism to separate said spindles and means to vary the length of time during which the spindles are separated when releasing a finished piece of work.

5. A grinding machine comprising a base, a grinding wheel rotatably mounted thereon, a pair of rotatable axially movable work supporting spindles to grip and support a work piece during the grinding operation, means including a cam mechanism to feed the grinding wheel toward and from the work through an invariable cam cycle, means operated in timed relation with said cam mechanism to adjust the time at which the work gripping spindles separate relative to the movement of said cam mechanism to release a finished piece of work and means to vary the length of time during which the spindles remain separated.

6. A grinding machine comprising a base, a grinding wheel rotatably mounted thereon, rotatable axially movable work supporting members adapted to support a work piece in operative relation with the grinding wheel, means to positively separate said members, means including a yieldable device to move the members towards each other to grip the work and means for controlling and varying the rate of such movement of the members towards each other.

7. A grinding machine comprising a base, a grinding wheel rotatably mounted thereon, rotatable axially movable work supporting members adapted to support a work piece in operative relation with the grinding wheel and an adjustable weight and dash-pot arranged to control the rate of movement of said supporting members toward each other in gripping a work piece.

8. A grinding machine comprising a base, a grinding wheel rotatably mounted thereon, a pair of rotatable axially movable work supporting spindles, one of which is movable axially toward and from the other, to grip and rotate a work piece, and means to move said spindles relatively toward and from each other, including an adjustable weight and dash-pot to control the rate of movement of said spindles toward each other in gripping a work piece.

9. A grinding machine comprising a base, a grinding wheel rotatably mounted thereon, a pair of rotatable axially movable work gripping and rotating spindles, means to move said spindles simultaneously toward and from each other, and an adjustable weight and dash-pot to control the rate of movement of said spindles toward each other in gripping a work piece.

10. A grinding machine comprising a base, a grinding wheel rotatably mounted thereon,

work supporting and rotating spindles adapted to support a work piece in operative relation with the grinding wheel, means to control the movement of said members including a weight and dash-pot to move said spindles toward each other to grip a work piece and positively actuated mechanism to separate said spindles after grinding to release the work piece.

11. A grinding machine comprising a base, a grinding wheel rotatably mounted thereon, work supporting and rotating members in axial alignment, a turret wheel to support a plurality of work pieces and present them successively to said members, means including a cam mechanism to feed the grinding wheel toward and from the work through an invariable cam cycle, positively actuated means operated in timed relation with the cam mechanism so arranged that the turret wheel rotates a sufficient distance to present a new piece of work into operative association with the work supporting members and the grinding wheel while the wheel is out of contact with the work.

12. A grinding machine comprising a base, a grinding wheel rotatably mounted thereon, a pair of rotatable work supporting spindles, one of which is axially movable towards the other, arranged to support and rotate a work piece in operative relation with the grinding wheel, a turret wheel to convey work pieces successively into alignment with said spindles, means including a cam mechanism to feed the grinding wheel toward and from the work through an invariable cam cycle, positively actuated means operated in timed relation with the cam mechanism to separate said spindles and thereby release the finished work piece into the turret and means actuated by said cam mechanism to permit the turret wheel to rotate a sufficient distance to present a new piece of work into substantial alignment with the work supporting spindles.

13. A grinding machine comprising a base, a grinding wheel rotatably mounted thereon, a pair of rotatable axially movable work supporting spindles to support and rotate a work piece in operative relation with the grinding wheel, a turret wheel to convey work pieces successively into alignment with said spindles, means including a cam mechanism to feed the grinding wheel toward and from the work through an invariable cam cycle, positively actuated means operated in timed relation with the cam mechanism to separate said spindles and thereby release the finished work piece, means actuated by said cam mechanism to rotate the turret wheel a sufficient distance to present a new piece of work into substantial alignment with the spindles and a yieldable mechanism to simultaneously move the

spindles toward each other to grip the new piece of work.

14. A grinding machine comprising a base, a grinding wheel rotatably mounted thereon, rotatable axially movable work supporting and rotating spindles, a turret wheel arranged to convey successive pieces of work into substantial alignment with the work supporting spindles, said turret being so arranged that the work piece moves into a position with its axis slightly below the axis of the supporting spindles, and work engaging members on the work supporting spindles which are shaped so as to grip the piece of work, center it and raise it out of contact with the turret for the grinding operation.

15. A grinding machine comprising a base, a grinding wheel rotatably mounted thereon, work gripping and rotating members, means including a cam mechanism to feed said grinding wheel toward and from the work through an invariable cam cycle, a rotatable turret wheel to convey successive pieces of work into operative position, means to hold said turret against rotation during the grinding operation and means operated in timed relation with said cam mechanism to rotate the turret wheel a sufficient distance to present a new piece of work into substantial alignment with said members.

16. A grinding machine comprising a base, a grinding wheel rotatably mounted thereon, work gripping and rotating members, means including a cam mechanism to feed said grinding wheel towards and from the work through an invariable cam cycle, a rotatable turret wheel to convey successive pieces of work into operative position, means including a pawl and ratchet wheel to control rotation of said turret and means operated in timed relation with said cam mechanism to actuate said pawl to rotate the turret wheel a sufficient distance to present a new piece of work into substantial alignment with said members.

Signed at Plainville, Connecticut, this 20th day of June, 1928.

CHARLES H. NORTON.
